UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

YARN SPINNING OR TWISTING APPARATUS.

SPECIFICATION forming part of Letters Patent No. 660,624, dated October 30, 1900.

Application filed May 11, 1900. Serial No. 16,287. (No model.)

To all whom it may concern:

Be it known that I, GEORGE O. DRAPER, a citizen of the United States, residing at Hopedale, county of Worcester, State of Massachusetts, have invented an Improvement in Yarn Spinning or Twisting Apparatus, of which the following description, in connection with the accompanying drawings, is a specification, like letters on the drawings representing like parts.

This invention has for its object the production of simple, practical, and novel apparatus particularly adapted for high-speed twisting or spinning frames wherein the spindle speed is from, say, ten to fifteen thousand revolutions per minute.

The present embodiment of my invention is adapted especially to all classes of vertical twisting where a traveler is used which takes its greatest bearing at its lower side.

Figure 1 is a diametral section, enlarged, of part of a spinning or twisting apparatus embodying one form of my present invention with the parts at rest, the spindle and bobbin being partly shown in dotted lines. Fig. 2 is a similar view showing the position of the rotatable member of the traveler-support or duplex ring when the apparatus is running at speed.

In the present embodiment of my invention I provide a duplex ring or traveler-support comprising fixed and rotatable members each having a traveler-race, said members being so arranged that the races are in substantial vertical alinement, the traveler revolving around the interior of the duplex ring, between it and the bobbin. The members *a* of the duplex ring are herein shown superposed one above the other, the member *a* having its foot *a'* extended to be engaged and held fixedly by the sheet-metal holder *h*, of well-known construction, suitably mounted on the ring-rail *R*, and the said member is shown as having an upturned annular flange *a''* at its top, forming a traveler-race. The rotatable member *b* is shown as a rather deep ring having at its upper end a laterally-extended exterior flange *b'*, which loosely enters an annular recess *a''*, formed in the fixed member *a* by the overhanging shoulder *a''* and a rib *c*, which is sprung into place after

the two members *a* and *b* are assembled. The ring *b* is thus free to rotate and to move radially and axially to a limited extent, and I prefer to make the lower member of the pair 55 rotatable, inasmuch as the lift of the traveler, due to the stress of the yarn, will gradually effect rapid rotation of said member as the spindle speed increases. The inner annular faces of the members *a* and *b* are substantially in axial alinement when running at speed, and I prefer to make the two members of the same internal diameter. The traveler *t* has a laterally-extended head *t'*, with its extremity bent down, as at *t''*, to loosely embrace 65 the flange or race *a''* of the fixed member, the lower end of the traveler being bent to form an upturned hook *t''*, which embraces the lower end of the web of the member *b*, such portion thereof forming the race for the traveler. I thus provide fixed and movable races for the traveler, the latter cooperating with both simultaneously.

Now when the frame is started up the member or ring *b* is resting by its flange *b'* 75 on the rib *c*, and the traveler will at first travel along two quiescent races; but as the speed increases the friction of the traveler on the movable ring will finally effect its rotation, and as the speed of rotation of the ring 80 approaches the speed of the traveler the former will rise from the supporting-rib *c* and will appear to "float," being sustained by the stress of the yarn as it passes to the bobbin *B* (partly shown in dotted lines, Fig. 1) on 85 the high-speed spindle *S* of any suitable type. The bearing of the traveler on the fixed member imparts a slight drag thereto and steadies the movement of the traveler and rotatable ring member as they move in unison. 90

I have not shown the parts of a spinning or twisting frame in detail, it being understood that they are all of usual construction, the yarn being led from usual delivery-rolls through a pigtail or guide-eye to the traveler. 95

My invention is, as will be manifest, of the so-called "rotary-ring" type, and it provides for the use of a simple and effective traveler support or ring which can be readily substituted in frames now in use by removing the 100 old ring and inserting my novel duplex ring in the old-ring holder.

Various changes may be made in details of construction and arrangement without departing from the spirit and scope of my invention.

5 Having described my invention, what I claim, and desire to secure by Letters Patent, is—

1. In a spinning or twisting frame, a duplex traveler-support composed of a fixed and a 10 movable member arranged one above the other and each having a race for a traveler.

2. In a spinning or twisting frame, a duplex traveler-support comprising a fixed annular member having a traveler-race, a movable 15 annular member also having a traveler-race and capable of gyratory movement under the stress of the yarn, said members being superposed one above the other.

3. The combination of a fixed ring having 20 an upturned flange, and provided with an internal recess, a rotatable ring capable of gyratory movement and having a laterally-extended flange to loosely enter said recess, and a traveler to engage the depending web of 25 the rotatable ring and the upturned flange of the fixed ring.

4. The combination of a fixed and a rotatable ring, the latter being capable of gyratory movement under the stress of the yarn, means 30 to support the rotatable ring vertically by or through the fixed ring, and a traveler in operative engagement with both of said rings.

5. In a spinning or twisting frame, a fixed ring having a traveler-race, and a rotatable, 35 radially and axially movable ring, also having a traveler-race, said races being located

one above the other, and a traveler to simultaneously engage the races and revolute between the rings and the bobbin.

6. The combination with a fixed ring having a traveler-race at its top, of a rotatable ring freely supported by and depending below the fixed ring and having a traveler-race at its lower end, means to limit gyratory movement of the rotatable ring due to stress of 45 the yarn, and a traveler revolute upon the races of the said rings.

7. The combination with a fixed ring having an upturned flange to form a race, said ring also having an integral, overhanging shoulder, a rotatable and radially-movable ring having a depending web and with a laterally-extended flange at its upper end, to extend beneath said shoulder, an annular restraining-rib on the fixed ring, beneath the 55 flange of the rotatable ring, and a traveler to simultaneously engage the lower edge of the rotatable ring and the race of the fixed ring.

8. In a spinning or twisting frame, a fixed and a rotatable ring of substantially equal 60 internal diameter and each provided with a traveler-race, said rings being arranged in axial alinement, and a traveler to simultaneously coöperate with the two races.

In testimony whereof I have signed my 65 name to this specification in the presence of two subscribing witnesses.

GEORGE O. DRAPER.
